UNITED STATES PATENT OFFICE

2,534,301

IMPACT HAMMER WITH ATTACHED WEAR MEMBER

Charles E. Sennholtz, Chicago, Ill.

Application July 29, 1948, Serial No. 41,243

5 Claims. (Cl. 241—197)

1

The present invention relates generally to rotary impact crushers or pulverizers, having particular reference to improvements in the revolving hammers for use therein.

The primary object of the present invention is to provide an improved hammer having a replaceable tip which is easily installed and removed and which is proof against accidental disengagement even under the most severe operating conditions. It is a more specific object of the invention to provide a hammer arm and tip therefor in which the engaging surfaces are formed in a novel manner so that all the forces acting thereon during the course of use, and particularly the centrifugal and impact forces, tend to cause increased wedging engagement.

It is another object of the invention to provide a pulverizing hammer which is efficient in operation, inherently strong and which is capable of withstanding the forces of abrasion and impact, all permanent engaging surfaces being effectively shielded against damage and wear. The hammer is, nevertheless, simple and straightforward of construction and inexpensive to manufacture, requiring a minimum of machining operations.

It is a more detailed object to provide in a pulverizing hammer an improved fastener or lock in which the elements are arranged for easy manipulation and are not subject to stress or damage due to impact even under abnormal conditions of use.

Other objects and advantages of the invention will become apparent as the description proceeds and in view of the accompanying drawings, in which:

Figure 1 is a rear elevation of a hammer and replaceable tip constructed in accordance with the present invention.

Fig. 2 is a side elevation in partial section taken along the line 2—2 of Fig. 1.

Fig. 3 is a top view of the replaceable tip with one wall thereof in partial section.

Fig. 4 is a perspective view of the hammer arm.

Fig. 5 shows the improved hammer tip in perspective with the face exposed as under operating conditions.

Fig. 6 is a rear perspective view of the hammer tip disclosed in Fig. 5.

Fig. 7 shows a modification in which the mounting bolt is integral with the replaceable tip.

While the invention is susceptible of various modifications and alternative constructions, I

2

have shown in the drawings and will herein describe in detail the preferred embodiment, but it is to be understood that I do not thereby intend to limit the invention to the specific form disclosed, but intend to cover all modifications and alternative constructions and uses falling within the spirit and scope of the invention as expressed in the appended claims.

Referring more particularly to the drawings, 10 an impact hammer 10 embodying the present invention is adapted for use in various types and kinds of crushers, pulverizers or mills. The hammer construction may be readily understood without reference to the details of the pulverizer 15 as a whole. It will suffice to say, therefore, that a plurality of such hammers are pivoted at the periphery of a rotating disk and are maintained in a radially extending direction due to the action of centrifugal force. The hammers are 20 swung successively into contact with a mass of rock, coal or similar frangible material which is broken up into a loose mass by the impact.

As disclosed in Figs. 1 and 2 the hammer 10 comprises a hammer arm or shank 11 and a hammer tip 12 secured to its lower portion. The hammer arm is pivoted pendulum-like at its upper end on a shaft 14 which is received in a bore 15. Rectangular in shape, the arm has a leading edge 16 and side walls 18, 19 extending 25 rearwardly therefrom. It will be noted that the cooperating tip 12 is generally box-like having a relatively massive impact face 22 and side walls 24, 25. Interiorly the tip is hollowed or channelled-out to provide a recess 26 into which the lower portion of the hammer arm 11 is slidably 30 inserted. When in position on the arm, the tip substantially encloses the entire lower portion of the arm. Preferably the face of the tip is provided with an upward extension 28 to protect the 35 leading edge of the arm and to serve as a mounting 40 for a threaded fastener.

In accordance with one of the aspects of the invention, the arm 11 and replaceable tip 12 are joined by a tongue and groove connection which 45 is so constructed that centrifugal force acting on the relatively massive tip 12 tends to wedge the tip onto the arm increasingly during normal use of the hammer. In the present construction this is accomplished by providing internal tongues 50 30, 31 on the interior walls of the tip and by relieving the lower portion of the arm to provide 55 downwardly angled engaging shoulders or ledges 34, 35. As shown in Fig. 2, the tongues make an angle A with respect to the radial dimension of the arm so that engagement is accompanied

by a small amount of radially outward movement. Thus, with the tongues 30, 31 engaged on the shoulders 34, 35, there is tendency for the tongues to "slide downhill" on the shoulders as the result of centrifugal action. Such movement is, however, limited by the wedging engagement to which more detailed reference will be made and ultimately by bottoming of the leading edge 16 of the arm on the forward wall of the recess 26. It will be apparent that due to the downward angling of the shoulders 34, 35 and the cooperating tongues 30, 31, assembly of the tip on the arms requires that the tip be slid rearwardly and downwardly into position when the tip and arm are assembled.

Provision is also made for firmly wedging the parts together as a result of forces resulting from normal use. This is accomplished in part by the specific tapered construction of the tongues 30, 31 and of cooperating grooves 38, 39 lying adjacent the shoulders 34, 35. As will be noted from the drawings, the grooves 38, 39 formed on the lateral faces of the hammer arm are tapered, the width of the grooves being appreciable at the point of intersection with the leading edge 16 of the hammer arm while the trailing portions thereof are considerably narrower. It will be clear upon inspection of Fig. 6 that the inserted tongues 30, 31 are likewise tapered both horizontally and vertically so that upon insertion into the grooves 38, 39 bearing will take place evenly on both the side walls and the roots of the grooves. Not only does such construction provide a firm grip between the tip and hammer arm, but it also results in a sturdy column-like construction of the tongues 30, 31 which flare evenly in the direction of the face 22 for absorbing the impact stresses.

In another aspect of the invention it will be noted that the grooves 38, 39 define a boss or enlargement generally indicated at 40 having side walls 18a, 19a and a lower surface 41 adapted for insertion into the recess 26. Further, the boss 40 is tapered both horizontally and vertically so that, from a structural standpoint, it may be compared to a truncated pyramid, with the leading portion of the boss being of reduced cross section. In order to utilize all of the gripping area thus made available, the walls of the recess 26 in the tip 12 are likewise tapered and to the same degree. Consequently, insertion of the boss 40 into the recess is accompanied by wedging at the surfaces 18a, 19a, 41 as well as on the shoulders 34, 35 previously referred to. It will be apparent, therefore, since all of the mating surfaces are tapered, that there are no surfaces which need be machined to a fine tolerance in order to insure smooth sliding engagement. As a matter of fact, the tip 12 may be a simple casting and may be constructed as illustrated without any machining whatsoever. Since it is unnecessary that the tip 12 be precisely "fitted" to the arm 11 to avoid looseness or play, it will be apparent that considerable dimensional variation is permissible, and the tips may be turned out very cheaply. The latter point is of particular interest when it is remembered that the tip must be replaced at intervals due to the abrasion by the pulverized material in which it operates. Where the tips are formed of cast steel it will be seen that the tapered surfaces provide proper draft for easy removal of the pattern from the mold.

One of the advantages resulting from the tapering of the boss 40 and the recess 26 is particu-

larly well illustrated in Figs. 2 and 3 where it will be seen that the lower and side walls of the tip 12 are flared into a thick supporting cross section in the region 42 without undue enlargement of the tip. This not only provides a strong columnar support for the peripheral portions of the impact face 22 which must take the brunt of the wear, but also provides considerable metal which may be worn away due to abrasion before replacement becomes necessary. As a result, it has been found that tips of the present construction may be kept in service for a length of time which compares favorably to relatively expensive hammer tips of the reversible type having renewable faces. The saving using the present type of tip is even greater than might be expected since taking the machine out of service and disassembling it at frequent intervals for renewing the tips becomes unnecessary.

To increase the gripping action and to provide a mounting for a fastening bolt the upward extension 28 of the face 22 carries a transverse tongue 45 on the rear portion thereof. This tongue includes tapered sides 48, 49 which are received in a registering notch 50 which is formed in the leading edge 16 of the hammer arm. While it will be apparent to one skilled in the art that the tongue 45 serves to retain the tip against radial displacement, it is to be particularly noted that the tongue is well adapted for preventing relative twisting to the tip 12 on the arm caused by severe impact at the lower portion of the impact face 22. In understanding this function of the tongue 45 it is helpful to consider the hammer tip as analogous to one's cupped hand and the tongue 45 as analogous to gripping finger tips resisting downward rotation of the hand.

In order to fasten the tip 12 on the arm 11 and to positively lock it in place thereon, a bolt 46 is provided which is received in a bore 53 drilled into the leading edge of the hammer arm. At its trailing end the bolt 46 includes a head 54 which is recessed in a countersunk hole 55. Preferably a fillister head cap screw is used.

At the forward end of the bolt 46 means are provided for threaded engagement. Preferably this is accomplished by recessing a nut 51 in a T slot 52 which lies behind the face 22 in a protected position. The latter has the advantage that the nut may be inserted immediately prior to installing the hammer tip. Consequently, the threads are not affected by the heat treating processes to which the tip may be subjected during manufacture to increase its strength and resistance to abrasion. If desired, however, the bolt may engage the tongue 45 directly as disclosed at 46a in Fig. 7. It will be apparent, too, that forming the bolt integrally with the tip and providing it with a fastening nut at its trailing end is included within the scope of the present invention. In those cases where an integral bolt (or stud) is employed, it is important to observe that the bolt and its cooperating bore 53 are angled downwardly at an angle which is the same as the angle A of sliding movement of the tongues 30, 31 in the cooperating grooves 38, 39. Regardless of which specific fastening means is employed, it will be apparent that the direction of pull on the tip 12 is in the same direction as the direction of relative sliding movement between the two. Because of the engagement of the tapered faces previously discussed, it has been found that the bolt is not subject to any stress other than that incident to its initial axial tightening.

In spite of the fact that the tip is wedged into firm engagement on the hammer by the forces incident to its use, it is significant that replacement is readily accomplished. It is merely necessary to remove the bolt 46 and to tap the worn tip 12 forwardly with a machinist's hammer. This immediately relases the wedging forces and enables the tip to be readily withdrawn. Since both the engaging surfaces and the fastening bolt are completely shielded, injury to the latter is completely avoided and a renewal tip may be quickly fastened in place.

I claim as my invention:

1. An impact hammer for rotary pulverizers comprising, in combination, a hammer arm adapted to be supported for bodily swing at one end and having lateral shoulders at the other end extending generally perpendicular to the longitudinal dimension of said arm, a hammer tip comprising a hollowed-out body portion and an impact face, said hollowed-out body portion having opposed inwardly directed tongues for engagement by the shoulders on said arm, said face portion having at its upper edge a transverse rearwardly facing tongue, said tongue having formed in the upper surface thereof a T slot for the reception of a nut, and a bolt extending through said arm for tightening engagement with said nut.

2. An impact hammer for rotary pulverizers comprising, in combination, a hammer arm adapted to be supported at one end for bodily swing, said arm being necked down at its opposite end to define a boss arranged in general alinement with the direction of swinging movement of said outer end, said boss having outer surfaces which flare both horizontally and vertically in a rearward direction, and a hammer tip having an impact face, said tip being channeled-out rearwardly of said face to provide internal surfaces registering with the outer surfaces of said boss, the flared nature of said surfaces enabling snug engagement of said tip in spite of surface inaccuracy.

3. An impact hammer for rotary pulverizers comprising, in combination, a hammer arm adapted to be supported at one end for bodily swing, said arm being necked down at its opposite end to define a boss arranged in general alinement with the direction of swinging movement of said outer end, said boss having a truncated pyramidal shape with the leading portion thereof being of reduced cross section, and a metal hammer tip having an impact face and channeled-out rearwardly of said face to form a rearwardly flaring recess for registering with said boss, said tip having a wedge-shaped cross section of metal bounding said recess and serving not only to reinforce said face under impact but to permit wearing away of the periphery of said face as a result of abrasion.

4. An impact hammer for rotary pulverizers comprising, in combination, a hammer arm adapted to be supported at one end, said arm

having a leading edge and generally parallel side surfaces adjacent thereto, said side surfaces each being relieved by a groove formed therein which intersects said leading edge and which extends rearwardly therefrom, a hammer tip of box-like construction having a massive impact face portion and side walls extending rearwardly therefrom, said side walls having formed therein opposed tongues adapted for registered engagement with the grooves in said hammer arm, a threaded fastener extending through said hammer arm toward the leading edge thereof, and a nut for engagement with the forward end of said threaded fastener, said impact face portion being channeled out to provide a rearwardly facing pocket which is T-shaped in transverse section for the reception of said nut and dimensioned to prevent turning of the latter.

5. An impact hammer for rotary pulverizers comprising, in combination, a hammer arm adapted to be supported at one end, said arm having a leading edge and bottom and side surfaces adjacent thereto, each of said bottom and side surfaces being flared outwardly in a direction rearwardly of the leading edge, said side surfaces each being relieved by a groove formed therein which intersects said leading edge and which extends at an angle rearwardly and downwardly therefrom, a hammer tip of box-like construction having a massive impact face and having bottom and side walls extending rearwardly therefrom to mate with corresponding bottom and side surfaces of said arm, said side walls having formed therein opposed tongues adapted for registered engagement with the grooves in said hammer arm, an upward extension on the face portion of said tip having a transverse rearwardly extending tongue and a rearwardly opening pocket, said arm having formed in its leading edge a notch for the receipt of said rearwardly facing tongue, a bolt extending through said hammer arm toward the leading edge thereof, and means disposed in said pocket for threaded engagement with said bolt so that said tongues may be drawn inwardly and downwardly into said grooves.
